DESIGN FOR A PHONOGRAPH NEEDLE

Peter L. Jensen, Western Springs, Ill.

Application March 13, 1944, Serial No. 112,884

Term of patent 14 years

(Cl. D26—14)

To all whom it may concern:

Be it known that I, Peter L. Jensen, a citizen of the United States, residing at 4716 Woodland Avenue, Western Springs, in the county of Cook and State of Illinois, have invented a new, original, and ornamental Design for a Phonograph Needle, of which the following is a specification, reference being had to the accompanying drawing, forming a part thereof; in which:

Figure 1 represents a front elevational view of a phonograph needle embodying my new design;

Figure 2 represents a side elevational view of the needle shown in Figure 1;

Figure 3 represents a rear elevational view of the needle shown in Figure 1;

Figure 4 represents a top plan view of the needle shown in Figure 1; and

Figure 5 represents a bottom plan view of the needle shown in Figure 1.

I claim:

The ornamental design for a phonograph needle, substantially as shown.

PETER L. JENSEN.
